UNITED STATES PATENT OFFICE.

HORACE CRAIGHEAD, OF BALLARD VALE, MASSACHUSETTS, ASSIGNOR TO
THE CRAIGHEAD & KINTZ COMPANY, OF SAME PLACE.

CENTRAL-DRAFT LAMP.

SPECIFICATION forming part of Letters Patent No. 471,507, dated March 22, 1892.

Application filed April 9, 1891. Serial No. 388,210. (No model.)

To all whom it may concern:

Be it known that I, HORACE CRAIGHEAD, of Ballard Vale, Essex county, and State of Massachusetts, have invented a certain new and 5 useful Improvement in Central-Draft Lamps, of which the following is a specification.

My improvement relates to central-draft lamps; and the object of the improvement is to facilitate the lighting of such lamps.

10 I will describe a lamp embodying my improvement, and then point out the novel features in a claim.

In the accompanying drawings, Figure 1 is a sectional elevation of the upper part of a 15 lamp embodying my improvement in condition for use. Fig. 2 is a similar view showing the burner part of the lamp in condition for lighting. Fig. 3 is a central vertical section of the wick-tube and the inner air-distributer.

20 Similar letters and numerals of reference designate corresponding parts in all the figures.

A designates the upper part of an oil reservoir or fount, which may be of ordinary form 25 and made of sheet metal.

B' B² designate the wick-tube of the lamp. This wick-tube is composed of two cylindric and concentrically-arranged shells B' B². The shell B' extends upwardly through a central 30 opening or collar a, with which the reservoir or fount is provided, and is intended to extend in the usual manner down through the bottom of the reservoir, so as to form a central draft-tube. The outer shell B² is here 35 shown as attached to an outer air-distributer C, which is detachably fitted to the collar a of the reservoir A. This air-distributer C may be fastened to the collar a by means of a bayonet-joint a' or any other device, or may be 40 simply held in place by friction. This shell B² when in place extends upwardly to a point on a level with the tip of the shell B' of the wick-tube.

D designates a tubular wick, which fills the 45 space between the shells B' B². As here shown, it is fitted to a carrier E, consisting of a band of sheet metal. It may be engaged with the carrier or band E by means of prongs on the latter or in any other suitable manner. The 50 carrier of course slides between the two shells

of the wick-tube. It is adjusted up and down by means of a ratchet-wheel F, mounted upon a shaft journaled in the air-distributer C and engaging with perforations formed in the carrier or band.

G designates the inner air-distributer, which consists of two conical shells g' g², arranged one above the other and connected with a tubular part g³, which is surmounted with a hollow head g⁴, which is perforated around the 55 circumference. Air ascending through the central draft-tube B' passes through the lower conical shell g' into the space between the shell B' and the part g³, and afterward passes through the upper conical shell g² and is discharged at the base of the flame. Air also passes from the shell B' into the part g³ and is discharged through the perforations of the head g⁴ into the flame. This air-distributer 60 G is, as here shown, supported by having its lower conical shell g' resting upon a bead or 65 inward projection b', formed on the shell B'. 70

H designates an air-distributer arranged above the air-distributer C and consisting of two shells h' h². The shell h² has its outer 75 portion constructed to form a chimney-gallery having resilient fingers h. At its inner edge it has an upwardly-turned rim or collar h³. The shell h' extends inwardly and at the inner edge is almost as small as the shell B² 80 of the wick-tube. This shell h' is perforated almost throughout its entire extent. Its outer extremity is made in the form of a downwardly-extending rim h⁴, which fits a corresponding rim h⁵, formed on the shell h². The 85 shell h' may be retained in the shell h² by means of a bayonet-lock or in any other desired manner. It is advantageous to make it detachable to facilitate cleaning. Air entering the air-distributer C will rise to the air-distributer H, and, after passing through the 90 perforations of the two shells h' h² of the latter, will enter the space within the chimney and pass to the outside of the flame. Neither shell of the air-distributer H is intended to 95 contact with the air-distributer C. It is advantageous to leave a space between these two air-distributers H and C for the circulation of air. By this means the air-distributer C may be kept cool. As the air-distributer 100

H does not contact with the air-distributer C, it must be supported by some other part. I have shown it attached to a cylindric shell I, surrounding and snugly fitting the outer shell 5 B² of the wick-tube. The rim or collar at the inner edge of the shell h² of the air-distributer H is fastened in any suitable manner to the shell I. The shell I is shown as provided with slots i, having an ascending portion 1 and a 10 horizontal portion 2, extending from the lower end of the ascending portion 1. The ascending portion 1 of each slot is shown as oblique or spiral. With these slots engage projections b², extending outwardly from the outer shell B² of the wick-tube. Obviously by 15 rotating the shell I by force applied to the air-distributer H through a handle h¹⁰ or otherwise the shell I will be caused to travel upwardly along the outer shell B² of the wick-tube, and after the shell I shall have traveled 20 the whole length of the slots i the horizontal portions 2 at the lower ends of the said slots will engage with the projections b², and the shell I will thereby be sustained in an elevated position. The shell I has an opening I' through it below the chimney-gallery, which 25 when the shell is in its upward or raised position affords access to the wick. The very firm bearing which the shell I will have upon the outer shell B² of the wick-tube prevents any 30 canting or tilting of the air-distributer H. Consequently the chimney and a shade, as well as all other parts supported by the air-distributer H, will not be liable to injury. 35 Preferably there will be grooves i' at the lower end of the slots i. These grooves may be made by bending the shell I outward.

They are intended to be deep enough to pass over the projections b². Thus they will render it possible to remove the shell I. Thus 40 constructed the shell I and of course all parts sustained by it will be detachably connected to the other parts of the lamp. When the shell I is rotated into such position that the upper ends of its slots i will contact with the 45 projections b², the latter will sustain the shell I and its appurtenances.

It will be seen that I afford provision for raising the chimney-gallery and upper air-distributer H, with their appurtenances, in 50 such manner that it will be possible to light the lamp without removing the chimney or shade.

What I claim as my invention, and desire to secure by Letters Patent, is— 55

In a central-draft lamp, the combination, with the reservoir or fount and wick-tube, of a chimney-gallery and a shell connected with the chimney-gallery and closely fitting the outer shell of the wick-tube and provided 60 with slots engaging projections on the wick-tube and consisting of obliquely-ascending and horizontal portions, and also provided with grooves extending from the slots downwardly to and having an outward opening at 65 the lower edge of the shell, substantially as specified.

In testimony whereof I have signed my name to this specification in the presence of two subscribing witnesses.

HORACE CRAIGHEAD.
